UNITED STATES PATENT OFFICE.

WILLIAM E. EWING, OF HOUSTON, TEXAS.

FURNACE.

1,333,104.

Specification of Letters Patent.

Patented Mar. 9, 1920.

Application filed May 13, 1919. Serial No. 296,880.

To all whom it may concern:

Be it known that I, WILLIAM E. EWING, a citizen of the United States, residing at Houston, in the county of Harris and State 5 of Texas, have invented certain new and useful Improvements in Furnaces, of which the following is a specification.

This invention relates to new and useful improvements in a furnace.

10 One object of the invention is to provide a furnace of the character described which has been specially designed for the burning of pulverized rice hulls, for fuel, and which is also adapted for utilizing other similar fuels, 15 such as chaff, sawdust, and the like. In the process of hulling rice, the disposition of the hulls has heretofore been a problem inasmuch as if they are burned in the ordinary furnace, great quantities of black ashes result, which are ejected from the smoke stacks, and contaminate the air to such an extent that in most cities, there are ordinances against using said hulls for fuel purposes. The same is true when it is sought to 20 utilize chaff, sawdust and the like as a fuel, and consequently, these products must be hauled away and disposed of in some other manner at considerable expense, and at a total loss. It is the object of this invention 25 to provide a furnace which will utilize these products in connection with the boiler for generating steam and which will entirely consume such fuels without contaminating the surrounding air with the ashes given off.

30 Another object of the invention resides in the provision of a furnace, which will generate great heat at little expense and by the use of which, the maximum fuel value of said products will be obtained.

35 With the above and other objects in view, the invention has particular relation to certain novel features of construction, arrangement of parts, and use, an example of which is given in this specification and illustrated 40 in the accompanying drawings, wherein:

Figure 1, shows an end view of the complete device shown partially in section.

Fig. 2, is a vertical sectional view,

Fig. 3, is a fragmentary sectional view

45 taken on the line 2—2 of Fig. 1 of the discharge pipe,

Fig. 4, is an enlarged transverse sectional

view of the discharge end of the air line showing the oil burner located therein, and

Fig. 5, is a perspective view of the casting 55 employed, shown partially broken away.

Referring now more particularly to the drawings, wherein like numerals of reference designate similar parts in each of the figures, the numeral 1, refers to the steam 60 chamber of the boiler underneath which are the water pipes 2, through which the water circulates, and in which the steam is generated, said steam entering the steam chamber 1, from said pipes through the water legs 3, 65 3. The boiler is mounted above the furnace, being sustained on the columns 4 in front and on the wall 5 in the rear. The rear part of the furnace contains a combustion chamber formed of the downwardly converging 70 walls 6 and 7, which are preferably lined with fire brick and underneath the lining of the wall 6, there is a coil pipe 8, which is heated from the combustion chamber and connected to it, there is a fan or blower 9, 75 provided to generate the amount of air current required according to the amount of fuel consumed, and to force said air through said coil pipe in which the air is heated, and from the coil pipe, 8, the airline 8' extends 80 forwardly underneath the furnace. From the airline 8' leads the upwardly extending pipes 10, 11 and 12, which are controlled by suitable gate valves. The pipe 10 discharges the heated air up through the perforated inclined bridge wall 13. The pipe 11 discharges the heated air up into the transverse hollow casting 14 whose upper 85 face is perforated and the pipe 12 discharges heated air up through the grate 15 from the 90 ashpit into the fire chamber 16. Behind this fire chamber, there is located a transverse baffle wall 17 composed of open brick work, and located between the hollow casting 14, and the grate of the ash pit. 95

The forward end of the pipe 8', is turned backwardly and enters the front end of the furnace, and within said backwardly turned end, there is located an oil burner of any desired form. The numeral 19, refers to a 100 fuel container, wherein the pulverized hulls or other pulverized fuel is stored. The fuel is delivered from said container by the conveyer 20, and is thereby discharged into the

down spout 21, which enters the pipe 8", in front of the burner 18. This down spout is formed with a cylindrical casing 22, and a pipe 23 leading from the steam chamber 1, 5 is coiled in said casing 21, through which hot steam is passed to dry the fuel before it enters the furnace. In heating up the furnace, the oil burner 18 is first used, and oil is used as a fuel until the furnace becomes 10 heated. When the furnace is hot, the fan or blower 9 is started, and the oil cut off, but the steam pipe 24, of the burner is left open, and the current of steam will answer as a jet or siphon to carry the fuel into the furnace 15 against the baffle wall 17, where combustion begins, and the current carries the unconsumed fuel and flame up along the bridge wall 13, and over into the combustion chamber, the flame and heated air passing up 20 among the water pipes 2, and heating the water therein, and the smoke and ashes passing on through the outlet conduit 25, into the smoke stack 26. Within this smoke stack are arranged the circular sprayers 27, 25 27, through which water is sprayed from the water pipe 28, to settle any ashes and unconsumed fuel contained in the smoke, and these 30 settling are carried down into the hopper-like bottom 29, of the smoke stack, and carried off through the water pipe 30. The principal part of the ashes will be retained in the combustion chamber and arranged underneath said chamber, there is the transverse discharge pipe 31, having an inlet 32, 35 which communicates with the combustion chamber, and through which the ashes enter said discharge pipe, and the ashes so entering said pipe are carried away by water circulating therethrough, or by steam which 40 may be jetted therein through the steam pipe 33. This pipe 31 enters the upper part of a suitable receiving vat 34, and the ashes are thereby delivered into the hopper 35, contained in said vat, through which the 45 ashes are delivered into the receptacle 36, into which the lower part of the vat is formed.

For the purpose of cleaning off the bridge wall 13, and keeping it free from any deposits of fuel or ashes, the steam jets 37 are provided through which a fan like jet of steam is projected up along the said wall, which sweeps off the ashes and unconsumed fuel, and delivers them into the combustion chamber and likewise, the inclined walls 6 and 7 of the combustion chamber are provided with steam jets 38, 38, arranged to project jets of steam down along said walls to keep them cleansed from the ashes which 60 may be deposited thereon.

By the use of this type of furnace, any kind of combustible pulverized material may be utilized as a fuel, thus resulting in the great saving of fuel, and generating a great heat for the production of energy necessary 65

in the operation of a plant, and effectually disposing of the objectionable products of combustion which would otherwise escape into and contaminate the surrounding atmosphere.

70

What I claim is:

1. A furnace for boilers having a combustion chamber in the rear end thereof formed with inclined walls which converge downwardly a discharge pipe underneath said chamber, and communicating therewith, and provided to receive the ashes therefrom, an air pipe entering the front of the furnace and formed into a coil underneath the chamber, a fuel down spout entering said air pipe through which fuel may be delivered to said furnace, means for delivering fuel to said down spout, and means for generating a fluid current through said air pipe whereby the fuel is discharged into the furnace.

85

2. A furnace for boilers, having a fire chamber, an inclined bridge wall located behind said chamber, said bridge wall being provided with perforations, a transverse hollow casting whose upper wall is perforated, located between said fire chamber and bridge wall, a combustion chamber formed with downwardly converging walls behind said bridge wall, an air pipe formed into a coil underneath the combustion chamber, said pipe continuing forwardly underneath the furnace and discharging air into said fire chamber, a current generator connected to said air pipe, and discharge pipes leading from said air pipe, one of which enters said casting and discharges air through the perforations thereof, and the other of which terminates underneath the bridge wall and discharges air through the perforations thereof.

90

3. A furnace for boilers, having a fire chamber, an inclined bridge wall located behind said chamber, said bridge wall being provided with perforations, a transverse hollow casting whose upper wall is perforated, located between said fire chamber and bridge wall, a combustion chamber formed with downwardly converging walls behind said bridge wall, an air pipe formed into a coil underneath the combustion chamber, said pipe continuing forwardly underneath the furnace and discharging air into said fire chamber, a current generator connected to said air pipe, discharge pipes leading from said air pipe, one of which enters said casting and discharges air through the perforations, and the other of which terminates underneath the bridge wall and discharges air through the perforations thereof, and steam nozzles arranged to discharge jets of steam along said bridge wall and along the walls of the combustion chamber, and provided for the purpose of cleansing said walls.

105

4. A furnace for boilers, having a combustion chamber in the rear end thereof formed 110

115

120

125

130

with inclined walls, which converge downwardly, a discharge pipe underneath said chamber, and communicating therewith, and provided to receive the ashes therefrom, an 5 air pipe arranged underneath the combustion chamber, said pipe extending forwardly and entering the front of the furnace, a down spout entering said air pipe, through which fuel may be delivered to the furnace, 10 means for delivering fuel to said down spout,

and means for generating current, through said air pipe, whereby fuel is discharged into the furnace.

In testimony whereof I have signed my name to this specification in the presence of 15 two subscribing witnesses.

WILLIAM E. EWING.
